TYPEWRITING MACHINE

Bernard J. Dowd, West Hartford, Conn., assignor
to Royal Typewriter Company, Inc., New York,
N. Y., a corporation of New York

Application March 17, 1933, Serial No. 661,389

9 Claims. (Cl. 248—16)

This invention relates generally to typewriting machines and more particularly to new and useful improvements in means for supporting such machines in a manner for effectively absorbing the shocks and vibrations incident to operation of such machines and for closing the bottom thereof against meddling and undue dust accumulation.

Among the objects of the invention is to provide a novel typewriting machine supporting and bottom closing unit comprising frame means having shock and vibration absorbing devices engageable with the machine to be supported and the table or desk for supporting the machine, and a bottom cover plate independently mountable on and removable from said frame means.

With the above and other objects in view which will more fully appear, the nature of the invention will be more clearly understood by following the description, the appended claims, and the several views illustrated in the accompanying drawings.

In the drawings:—

25 Figure 1 is a fragmentary side elevation illustrating the invention in use, parts being broken away and in section.

Figure 2 is an inverted plan view parts being broken away and in section.

30 Figure 3 is an enlarged detail central vertical longitudinal section taken through one of the side rails or channels, parts being broken away and the cover plate being shown released and removed in dot and dash lines.

35 Figure 4 is a detail vertical cross section taken on the line 4—4 on Figure 3.

Figure 5 is a detail perspective view illustrating one end of one of the side rails or channels.

40 Figure 6 is a detail perspective view of one of the soft rubber cushioning or insulator pads.

Figure 7 is a detail perspective view of the removable cover plate.

45 Figure 8 is a detail sectional perspective view illustrating a modified form of removable cover plate.

Figure 9 is a fragmentary sectional perspective view illustrating a modified form of frame means and removable cover plate, the latter being shown separated from said frame means.

In the drawings in which like reference characters indicate like parts in all of the figures, A generally designates a typewriting machine, B the side walls of the frame thereof which 55 extend forwardly to accommodate the keyboard

and having foot portions C equipped with the usual threaded sockets D by which supporting feet are ordinarily secured to the frame, and E the rear frame wall which joins the side walls B.

All of the above parts will be recognized as conventional typewriter parts and in themselves form no part of my present invention except insofar as they combine with the shock and vibration absorbing and dust protecting unit described hereinafter.

My improved unit, in the form thereof shown in Figures 1 to 6 of the drawings, includes a pair of right and left frame members in the nature of side rails or U-shaped channels 5 preferably formed of sheet metal as shown in Figures 1 to 5. Each channel 5 is provided at its rear end with a lateral cutout 6 in order to avoid engagement with the rear frame wall E, and at its front end with an end cutout 7 to avoid engagement with the keyboard accommodating extensions of the side walls B of the typewriter frame. Each of the channel members 5 is also provided with an end enlargement 8 to accommodate the positioning of cushioning or insulating pads 9 of soft rubber or other suitable yieldable material, see Figures 2, 5 and 6.

Secured to the under face at each end of each channel member 5, through the medium of spot welding or other suitable securing means as indicated at 10, is an inverted metal cup or embordering seat 11 adapted to receive a cupped rubber supporting foot 12 as shown in Figures 3 and 5. The channel members 5, the cushioning pads or blocks 9, the cups 11, and the feet 12 are apertured to receive flat headed securing screws 13 adapted to enter the sockets D in the typewriter frame foot portions C as shown in Figure 3 of the drawings for the purpose of securing the channel members 5 to the typewriting machine frame with the supporting feet in position for supporting the channels above the desk or table or other support upon which the machine is mounted and the typewriting machine frame above the rails and suitably insulated therefrom by the pads 9 as shown in Figures 1 and 3. Each channel member 5 is provided with a threaded bushing 14 adapted to receive a securing screw 15 by which said channel or rail 5 may be suitably secured upon the desk or table or other supporting means 16 as shown in Figure 1.

Each side rail or channel 5 is also provided with a pair of reinforced threaded sockets 17 in which large headed clamping screws 18 are 110

operable, said screws being beaded over as at 19 to prevent complete removal thereof from their receiving sockets.

In order to join the channel members 5 to 5 form a unit and to completely close the under surface of the typewriter or other machine frame so as to protect it from excessive dust accumulation and also to serve as a collecting means for erasure dust, I provide a cover plate 20 which 10 preferably is constructed of sheet metal, as shown in Figure 7 of the drawings, corrugated as at 21 and flanged at its front and rear edges as at 22 to impart suitable rigidity and having its lateral edges which lie parallel the channel 15 members 5 equipped with laterally directed pairs of mounting lugs or ears 23. The ears 23 are provided with open slots 24 all directed in a common direction or longitudinally as shown in Figures 2 and 7.

20 By reason of the provision of the cover plate mounting lugs 23, 24 and the positioning thereof of complementary to the position of the clamping screws 18 with which the channel members 5 are provided, provision is made for conveniently 25 securing the cover plate to the channel members 5 or removing said plates from engagement with said channel members. By relieving the screws 18 as indicated in dot and dash lines in Figure 3 of the drawings, the plate 20 may be 30 moved upwardly so that the slots 24 will align with the screws 18 and then shifted rearwardly to enable said screws to seat within the bottoms of said slots. By then tightening the screws 18, the cover plate will be securely clamped beneath 35 the channel members 5.

From the foregoing, it will be observed that the channel members 5 constitute frame means and when joined by the cover plate 20 as just above described, contribute in forming a shock and vibration absorbing supporting and dust 40 protecting unit.

I am aware that dust protecting plates have heretofore been provided but all such structures of which I am aware are clamped to the typewriter or other machine base by the same means which serve to mount the supporting feet and thus it is necessary to remove the feet when removing the plate, frequently resulting in marring of furniture because of removal of the protective devices. The advantages of my construction will therefore be obvious, it being possible to conveniently remove the cover plate 20 so as to render the bottom mechanisms of the machine accessible for observation or servicing 50 without removal of the two side channels holding the supporting feet 12 and the cushions or pads 9, thus preventing unnecessary defacement of furniture.

In Figure 8 of the drawings, I have disclosed 60 a modified form of cover plate generally designated 25 in which the central portion is depressed or dished as at 26. Such a plate may be used in conjunction with machines in which parts of the mechanism have movement below 65 the normal plane.

In Figure 9 of the drawings, I have disclosed 70 another modified form of the invention in which the frame means comprises an open substantially rectangular frame including side rails generally designated 27 and joined by front and rear cross bars 28. In this form of the invention, the frame edge defining the opening adapted to be closed by the cover plate may be corrugated or beaded as at 29 and the front and rear edges 75 of the cross bars may be flanged as at 30 to im-

part the desired rigidity. The removable cover plate 31 may have the slotted ears or mounting lugs thereof beaded as at 32 to suitably fit the beading 29 extending along the side rails 27.

Aside from the slight differences in construction of the frame means and the cover plates shown in Figures 8 and 9, the parts employed in these modified forms are assembled and function in the same manner previously described.

In the foregoing description, I have disclosed a simple and efficient shock and vibration absorbing supporting and protecting unit including suitably insulated framing means attachable to a typewriter or other machine frame and which are in turn removably secured to a desk, table or other support, and a protective cover plate which may be applied to and removed from the framing means without disturbing the connection thereof with the machine frame.

I claim:—

1. The combination with the typewriting machine frame, of an open bottom support frame means, directly secured in close proximity to and removable from the machine frame, and a dust cover plate closely underlying the machine frame and independently removably secured to said frame means whereby said open bottom support frame means and said dust cover plate are readily removable as a unit or said cover plate individually removable without disturbing the mounting of said open bottom support frame means.

2. The combination with the typewriting machine frame and the foot portions thereof, of an open bottom support frame means, a shock and vibration absorbing foot and a shock and vibration absorbing cushion respectively underlying and overlying a frame means portion beneath each machine frame foot portion, means to secure each foot and cushion and the intervening support means portion to the machine frame foot portion which they underlie, and a dust cover plate underlying the machine frame and independently removably secured to said frame means.

3. The combination with the typewriting machine frame and the foot portions thereof, of an open bottom support frame means, a shock and vibration absorbing foot underlying a frame means portion beneath each machine frame foot portion, means to secure each foot and the overlying support means portion to the machine frame foot portion which they underlie, and a dust cover plate underlying the machine frame and independently removably secured to said frame means.

4. The combination with the typewriting machine frame, of support frame means secured to and removable from the machine frame, a dust cover plate underlying the machine frame and having spaced pairs of open slotted mounting ears the slots of which project in a common direction, and means depending from the frame means and releasably engageable with the mounting ears to removably secure the cover plate to said frame means.

5. The combination with the typewriting machine frame including side wall portions, a support frame channel underlying and removably secured to each side wall portion, shock and vibration absorbing means depending from each channel, shock and vibration absorbing means interposed between each channel and the respective side wall portion, and a dust cover plate underlying the machine frame and inde- 150

pendently removably secured to said channels.

6. The combination with the typewriting machine frame having side wall portions including foot portions, a support frame channel underlying each side wall portion, a foot of resilient material beneath each end of each channel, a cushion of yieldable material overlying each end of each channel, means for securing each end of each channel and the foot and cushion respectively underlying and overlying it to a respective foot portion, and a dust cover plate underlying the machine frame and independently removably secured to said channels.

7. The combination with the typewriting machine frame having side wall portions including foot portions, a support frame channel underlying each side wall portion, a foot of resilient material beneath each end of each channel, a cushion of yieldable material overlying each end of each channel, means for securing each end of each channel and the foot and cushion respectively underlying and overlying it to a respective foot portion, a dust cover plate underlying the machine frame and having edge portions paralleling the channels, a pair of open slotted mounting ears projected laterally from each plate edge portion, the slots in said ears being directed and opening in a common direction, and means depending from the channels 30 and releasably engageable in said slots to removably secure the cover plate to said frame means.

8. A dust protector and supporting unit for typewriting and like machines comprising an open bottom supporting frame means, yieldable feet and cushions for respectively supporting said frame means and for engaging a typewriter or like machine frame when the latter is mounted on the unit, means to secure the frame means to such machine frame, a dust cover plate, and means independent of said first mentioned securing means to removably secure the plate to said frame means. 80

9. A dust protector and supporting unit for typewriting and like machines comprising a pair of channel members spaced apart a distance for underlying side wall portions of a typewriter or like machine frame, a foot of yieldable material beneath each end of each channel, a cushion of yieldable material overlying each end of each channel, headed screws passing through the yieldable feet and cushions and said channels for securing said channels to frame portions of a typewriter or like machine, a dust cover plate underlying the machine frame and having edge portions paralleling the channels, a pair of open slotted mounting ears projected laterally from each plate edge portion, the slots in said ears being directed and opening in a common direction, and means depending from the channels and releasably engageable in said slots to removably secure the cover plate to said frame means. 95 100 105
